US0D1018053S

(12) **United States Design Patent** (10) **Patent No.:** **US D1,018,053 S**
(45) **Date of Patent:** **** Mar. 19, 2024**

(54) **STORAGE CASE**

(71) Applicant: **EPOCH COMPANY, LTD.**, Tokyo (JP)

(72) Inventor: **Ryo Sakai**, Tokyo (JP)

(73) Assignee: **EPOCH COMPANY, LTD.**, Tokyo (JP)

(**) Term: **15 Years**

(21) Appl. No.: **29/791,888**

(22) Filed: **Feb. 16, 2022**

(30) **Foreign Application Priority Data**

Aug. 18, 2021 (JP) ..... 2021-017743 D

(51) **LOC (14) Cl.** **03-01**

(52) **U.S. Cl.**

USPC **D3/271.1**

(57) **CLAIM**

The ornamental design for a storage case, as shown and described.

DESCRIPTION

FIG. 1 is a perspective view of the top, front, and right sides of a storage case showing my new design;

FIG. 2 is a perspective view of the rear, bottom, and left sides thereof;

FIG. 3 is a front view thereof;

FIG. 4 is a rear view thereof;

FIG. 5 is a top plan view thereof;

FIG. 6 is a bottom view thereof;

FIG. 7 is a right view thereof; and,

FIG. 8 is a left view thereof.

The broken lines shown are included for the purpose of illustrating portions of the article which form no part of the claimed design.

1 Claim, 8 Drawing Sheets
